UNITED STATES PATENT OFFICE.

JOHN P. WILDMAN, OF PORTLAND, OREGON.

COMPRESSOR.

Application filed March 26, 1925. Serial No. 18,480.

My invention relates to pumps and compressors, and is especially directed to compressors used in a refrigerating system for compressing the gaseous refrigerant.

5 In a compressor of this character, and especially in those compressors in which the refrigerant to be compressed is taken in through the crank case, an excess amount of oil is commonly forced up into the working 10 barrel of the cylinder by the pressure of the gas which has leaked past the piston into the crank case and the oil thus forced up is pumped out into the expansion coils. The oil forms a coating on the bore of the coils 15 which serves as an insulating medium to prevent efficient radiation through the walls of said coils. The particular object of my invention therefore is to arrange the parts in a compressor of this character so that its 20 tendency to pump oil out of the crank case will be eliminated in a relatively simple manner.

Another feature to be contended with in compressors of this character is that the 25 gaseous refrigerant leaks past the piston and into the crank case and builds up relatively high pressure therein. The crank case must be made air-tight to prevent the gas from escaping to the room, and thus when a relatively high pressure is set up in the crank case, it necessitates very tight packing and stuffing boxes.

The introduction of ammonia gas into the crank case also causes the oil to foam and 35 froth and the foamy particles are easily forced into the cylinder by the pressure of the gas within said crank case. A further object of my invention is to provide devices by which the refrigerant above the piston 40 and the lubricant in the crank case can be kept separate from each other so as not only to prevent pressure from being built up in the crank case, but also to eliminate the harmful effects caused by the refrigerant being admitted into contact with the lubricant.

45 My invention may be said to consist in forming the piston element with two heads and arranging intermediate the said heads, a circumferential chamber. Said chamber 50 is vented, the contents preferably being withdrawn through a branch of the intake pipe for the refrigerant, whereby the refrigerant which leaks past the piston and enters said chamber, is withdrawn before it can escape 55 into the crank case. Excessive pressure, therefore, is prevented from being set up in

the crank case which would tend to cause the lubricant contained therein to be pumped out due to a difference in pressure in said crank case, and in the space above the piston 60 during its suction stroke.

To produce a machine, in which the parts are of such size as to withstand the constant usage, to which a refrigerant compressor is subjected, experience has proven that the cross-head should be of greater size than the piston so that sufficient bearing surface, and 65 large enough pins can be provided to withstand the pressures and wear to which these parts are subjected. In my invention I propose to form the intermediate chamber, here- 70 before referred to, by causing said spaced piston and said cross-head each to seal a portion of the bore of the cylinder. When said piston and said cross-head are of un- 75 equal size, a pumping action will be produced which would cause oil to be withdrawn from the crank case and forced into the working branch of the cylinder. The object of my invention, therefore, is to provide devices 80 by which a piston, and a cross-head in the form of a piston and of unequal size, can be used in the same cylinder and by which the resulting pumping action will be eliminated.

I attain this object by providing two ad- 85 jacent cylinders with cylindrical pistons and cross-heads each reciprocating snugly in the bore of each of said cylinders. The piston and cross-head in each cylinder is connected together by a portion which is smaller in di- 90 ameter than said bore so as to provide a chamber within said bore circumferentially about said portion. The cross-head and piston in each cylinder are of unequal size but are exactly equal to the corresponding cross- 95 head and piston in the adjacent cylinder. The connected piston and cross-head in one cylinder is arranged to be reciprocated op- 100 positely to the corresponding piston and cross-head in the adjacent cylinder. By pro- viding a passageway between said adjacent 105 cylinders which connects the chamber in each, I cause the summation of the volume of said chambers and said passageway to re- main constant. This is for the reason that

when one piston and cross-head moves down- 110 wardly to tend to produce a partial vacuum in the chamber between the same, the pis- ton and cross-head in the adjacent cylinder moves upwardly to compress the contents thereof. Inasmuch as the diameter of said parts is relatively the same in the adjacent

cylinders, the displacement of each exactly corresponds to the displacement of the other and there is no resultant change in the pressure of the gases therein.

5 A further and more specific object of my invention is to provide a novel valve arrangement in said compressor, in which the valves are arranged wholly within the cylinder head and are removable therewith. The intake and discharge valves are thus independent of the pistons and are preferably arranged concentric one within the other, with the intake valve encompassed by the discharge valve. The outer or encompassing valve is provided with a plurality of closure elements held, in place by a single spring controlled element which is arranged to act uniformly upon all of said closure elements.

10 The details of construction and mode of operation are hereinafter described with reference to the accompanying drawings, in which:

15 Fig. 1 is a longitudinal section through a compressor having two cylinders arranged side by side;

20 Fig. 2 is a plan section taken on the line 2—2 of Fig. 1;

25 Fig. 3 is a plan section taken on the line 3—3 of Fig. 1; and

30 Fig. 4 is a vertical section taken on the line 4—4 of Fig. 3.

35 My compressor comprises two cylinders *a* which are mounted upon a crank case *a*⁵ which acts as a support therefor. As is common in crank cases of this character, the crank case for both cylinders is not divided by a partition and thus the portion under each cylinder communicates freely with the other. Said cylinders are preferably cast in a single unit and are water jacketed as *a'*. The compressor shown in the accompanying drawings has two cylinders in which the piston elements *b* and *c* reciprocate. Each piston element has two heads *b'* and *b*², and *c'* and *c*². The heads *b'* and *c'* constitute the piston heads which operate in the working barrels *d* and *e*, and the heads *b*² and *c*² constitute cross-heads which reciprocate in the cylindrical guides *f* and *g*. As can be noted in Fig. 1, the working barrels are substantially smaller in diameter than the cylindrical guides. The working barrels are separated by a water jacket space *a*², while the cylindrical guides *f* and *g* are separated merely by a partition *a*³ which terminates in a plane substantially in alinement with the bottom of the skirts, which constitute the working barrels *d* and *e*. The partition *a*³ is arranged equidistant between the bottom portions of said skirts, and thus a communicating passageway *h* is provided which connects the cylindrical guide *f* with the cylindrical guide *g*. The piston elements *b* and *c* are driven in time oppositely with each other by the connecting rods *i* and *j*, respectively.

That is, as shown in Fig. 1, when the piston element *b* is at upper dead center, the piston element *c* is at lower dead center, and thus when the position of one is reversed the other one is changed similarly. For this reason the spaces above the cross-heads *b*² and *c*², and below the pistons *b'* and *c'*, and the passageway *h* through the transverse wall portion *a*⁴ of the cylinder, remain constant even though the pistons *b'* and *c'* are smaller than the cross-heads *b*² and *c*².

10 When the piston element *c* moves downwardly, as shown in Fig. 1, and the piston element *b* moves upwardly, the contents of each of said spaces is permitted to pass through the passageway *h* so as to be equalized in pressure. When the position of said piston elements change oppositely the contents are permitted to pass through said passageway *h* into the opposite side. The pistons *b'* and *c'* are provided with a plurality of sealing rings *j* and *j'* to prevent the gas in the working barrel from escaping past said piston. Experience has proved that sealing rings maintain an efficient seal but permit a slight leakage of gas to escape to the crank case if means are not provided for catching and returning the same to the circulatory system. I thus connect a branch *k* of the intake pipe *k'* in the communicating passageway *h* above the partition *a*³. In said branch *k*, I place a check valve *k*³ which permits said gases to be withdrawn from said space but prevents the return flow therethrough past said check valve. Whenever the pressure in the suction pipe *k'* becomes lower than that in the spaces between pistons of cross-heads, the check valve *k*³ opens, allowing the passage of gas from said spaces into the intake pipe *k'*.

15 The cross-heads *b*² and *c*² are each provided with single sealing rings *l* and *m*, which permit a gradual passage of gas and a slight amount of oil to escape, to serve to lubricate all portions above the ring.

20 The cylinder head *n* serves as the head for both cylinders and is cast in a single unit, and is held down to the cylinder casting by studs *n'*. I mount valve cages *o* and *p* in said head, as shown in Fig. 1. Said valve cages comprise disc portions *o'* and *p'*, having tubular extensions *o*² and *p*² extended upwardly therefrom. Said disc portions *o'* and *p'* are recessed in the cylinder block directly above the working barrels *d* and *e* and are arranged so that their upper surfaces lie substantially flat with the upper surface of said cylinders. By arranging said valve cages in this manner, I am able, by providing single gaskets *q* between the cylinder head *n* and cylinder *a*, not only to provide a sealing medium between the cylinder and said head, but also to provide a seal for the valve cages, as well. This is for the reason that said gaskets extend about the re-

cess in the cylinder in which said disc portion or the valve cages are seated. The intake valves r and s are mounted centrally within said tubular extensions o^2 and p^2 and are preferably of the mushroom type, as shown in Fig. 1. Valve springs r' and s' tend to hold said valves upon their seats on the undersurface of the disc portions o' and p' , respectively. The intake pipe k' connects into a header or gland t which fits upon the top of said cylinder head and distributes the refrigerant to both cylinders. The gaskets or packing material u and u' about the tubular portions o^2 and p^2 are held in place by a header or gland t . Said packing material or gaskets provide an air-tight passageway between the intake pipe and the working barrels.

The discharge pipes k^2 are connected to the working chamber through three ball controlled ports v and w on the working chambers d and e , respectively. Said ports are spaced equidistant about the intake port directly above said working chambers and the balls v' and w' are held tightly against the seats by springs x and y which bear against holding rings x' and y' , respectively, in the working barrels d and e .

A cored out aperture x^2 or y^2 is arranged about each respective tubular extension o^2 and p^2 , respectively, to provide a passageway for the discharged refrigerant. Said discharged refrigerant passes from said cored out portion through the pipe k^2 . The valves and the valve cages are removable from the cylinder, with the cylinder head, to expedite the grinding of said valves or replacement of the parts therein.

The operation of my compressor is as follows:

The gaseous refrigerant to become compressed, is drawn into the compressor through the intake pipe k' and is emitted therefrom through the discharge pipes k^2 . The branch intake pipe k communicates with the main intake pipe and thus is subjected to suction by the compressor each time the piston therein produces a region of reduced pressure and thus the same conditions of pressure are maintained in the space be-

tween the heads of the piston elements, and is maintained in the intake pipes.

Starting with the piston element at upper dead center as in the left hand cylinder in Fig. 1, the movement of the piston head b' downwardly will cause relatively reduced pressure in the working barrel d will tend to unseat the intake valve r and permit the gas to be introduced into said barrel from the intake pipe k' . When said piston head b' approaches lower dead center, and the reduced pressure is compensated by gas flowing from said intake, the valve spring r' will move the valve back upon its seat to prevent further gas from being admitted.

The movement of said piston head upwardly causes the gas to be compressed and when said compression is built up to such a degree as to overcome the springs x which hold the ball checks x' in place, said balls are lifted from their seat by said pressure and the gas is permitted to flow outwardly into the discharge line k^2 .

Said piston elements b and c move oppositely and thus, while one piston is compressing the gas and displacing it from a cylinder, the other is drawing in a charge of gas from the intake line. Such pistons moving in time oppositely to each other, thus causes the volume of the space between the heads of the piston elements to remain constant, as has been heretofore brought out, because of the connecting passageway h .

I claim:

In a compressor: two pairs of aligned and connected pistons and crossheads, the pistons of each pair being smaller than the crosshead of the same pair; parallel pairs of cylinders for each of said pistons and crossheads; a wall common to both of the larger cylinders and extending upwards to terminate in a space between the smaller cylinders, said space being an equalizing passageway between the housings of said pistons; a crank shaft operating said crossheads oppositely; and means upon said crossheads to seal the crank case from the space thereabove.

JOHN P. WILDMAN.
